FLAT FOLDING CUP

Robert Blaser, Featherbed Lane, Branford, Conn.
Continuation of abandoned application Ser. No. 57,763,
Sept. 22, 1960. This application Mar. 14, 1962, Ser.
No. 181,228

1 Claim. (Cl. 220—6)

This invention relates to collapsible drinking cups in general, and to flat folding cups in particular.

This application is a continuation of my prior application, Serial No. 57,763, filed September 22, 1960.

A cup of the general type with which the present invention is concerned is disclosed in the patent to Titchborne, No. 1,117,109, dated November 10, 1914. This cup consists of two elongated odd-shaped leaf-like members or halves of resiliently flexible material which have opposed floating pivot connections near their opposite ends and are flat and superposed in the unfolded condition of the cup. To fold the cup for use, the user grasps the leaf-like members, then flexes them between their pivot connections and simultaneously turns them in opposite directions about their pivot connections into partial cone formations until they complement each other in a cone-like receptacle, in the course of which the inner member passes through a zone of interference of the outer member. After use, the cup may be unfolded by forcing its members in the reverse direction until they snap back into their flat superposed condition. However, this cup was found to be quite unwieldy and requiring considerable effort and dexterity to manipulate, especially in folding it into cup form, and more important, when folded by the average user was found to leak so prohibitively as to be to all practical intents and purposes useless as a drinking cup.

It is the primary aim and object of the present invention to provide a folding cup of this type which for its folding and unfolding requires hardly any effort and dexterity on the part of the user, and is assuredly leak-proof when folded by any, and even the clumsiest, user.

It is another object of the present invention to provide a cup of this type of which the cup members with their floating pivot connections are so arranged that for their folding into and unfolding from cup form they require mostly mere sliding on each other followed by simple pivoting about their pivot connections, and vice versa, thereby to achieve their aforementioned manipulation with hardly any effort and dexterity on the part of any user.

It is a further object of the present invention to provide a cup of this type of which the cup members with their pivot connections are further arranged so that on their folding into cup form the inner member will yield through the interference zone of the outer member, and both members will on their continued folding beyond the interference become resiliently flexed with an increasing force which on release of either member will snap both members back into cup form so forcefully as to drive the inner member sufficiently into the interference zone of the outer member to form at their line of contact an assuredly leak-proof seal between them.

Other objects and advantages will appear to those skilled in the art from the following, considered in conjunction with the accompanying drawings.

In the accompanying drawings, in which certain modes of carrying out the present invention are shown for illustrative purposes:

FIG. 1 is a top view of an unfolded cup embodying the present invention;

FIG. 2 is an end view of the same unfolded cup;

FIG. 3 is a fragmentary top view of the same cup in a partly folded condition;

FIG. 4 is a section taken on the line 4—4 of FIG. 3;

2

FIG. 4A is a section through the cup in further folded condition;

FIG. 5 is a top view of the cup in an overfolded condition into which it is normally manipulated for its snap-back into normal folded condition;

FIG. 5A is a fragmentary top view of the cup at an intermediate stage of its folding;

FIGS. 6 and 7 are top and side views, respectively, of the cup in its normal folded condition;

FIG. 8 is a section through the folded cup as taken on the line 8—8 of FIG. 6; and

FIG. 9 is a fragmentary top view of a modified unfolded cup of the present invention.

Referring to the drawings, and more particularly to FIGS. 1 to 8 thereof, the reference numeral 20 designates a cup of folding type which consists of two members or halves 22 and 24 that are pivotally connected. The cup members 22 and 24, which are made of relatively thin and resilient material and preferably metal such as stainless steel, are flat and superposed in the unfolded condition of the cup (FIGS. 1 and 2) and are in the form of complementary partial cones in the folded condition of the cup (FIGS. 6 to 8).

The cup members 22 and 24 are odd-shaped for their resilient formation into partial cones which complement each other in the folded condition of the cup to form a sealed receptacle. The cup members 22 and 24, while odd-shaped, are presently individually symmetrical about a median line or axis x which extends at right angles to another line x' passing through, and intersects the latter line midway between, the pivot connections 26 between the cup members (FIG. 1). The cup members are also generally elongated in the direction of the line x'.

The shapes of the cup members 22 and 24 may vary quite widely, depending on the desired size and form of the unfolded cup. As to the present form of the cup member 22, its peripheral edge 28 is shaped (FIG. 1) to form the desired base of its partial cone form in the folded cup (FIGS. 6 to 8), while its edge 30 is shaped to conform to the curvature of the cup member 24 in its partial cone form in the folded cup at the line of contact of both cup members to seal the folded cup thereat. The sealing edge 30 of the cup member 22 is over the greater part of its length presently shaped (FIG. 1) to conform in the folded cup to the line of intersection x'' between the cup member 24 in its partial cone form and a plane normal to the base of the latter (FIGS. 6 and 8). As to the present form of the cup member 24, its edge 32 (FIG. 1) is shaped to form the desired base of its partial cone form in the folded cup (FIGS. 6 to 8), while its edge 34 is shaped to terminate its partial cone form outside the confines of the receptacle of the folded cup in the first place and along a desired smooth line in the second place (FIGS. 7 and 8).

The pivot connections 26 between the cup members 22 and 24 near their opposite ends are of floating type and comprise pivots 36 and slots 38, of which the pivots 36 are presently and preferably provided on the cup member 22 and the slots 38 are provided in the other cup member 24. The pivots 26 and slots 38 are presently equally spaced from the median line x and the slots 38 are identically inclined to this median line x.

Opposite end lengths 30' of the edge 30 of the cup member 22 are presently formed by ear extensions 40 (FIG. 1) which in the folded cup extend deeper into the cone-shaped cup member 24 than any other part of the cone-shaped cup member 22 (FIGS. 6 and 8).

To fold the flat cup, the members 22 and 24 are grasped near and substantially midway of their respective edges 28 and 32 and drawn apart until the pivots 36 reach the opposite ends 38'' of the slots 38 (FIGS. 3 and 4). In thus drawing or sliding the cup members apart they are

flexed into preliminary partial cones by cam action between the pivots 36 and respective slots 38, with the cup member 22 being compelled into a partial cone of much smaller slant than that of the cone-shaped member 24 primarily by the curvature of the latter at and near the pivots 36, as will be readily understood. While still grasping the cup members in the intermediate folded stage of FIGS. 3 and 4, preferably more inwardly now, they are then turned out about their pivot connections 26 through the passing stage of and in the direction of the arrows 42 and 44 in FIG. 4A until they are preferably over-folded to an extent like or similar to that shown in FIG. 5, whereupon either cup member is released for resilient spring-back of both cup members into their normal folded receptacle-forming condition in which the edge 30 of the cup member 22 bears against and conforms to the curved surface of the cup member 24 throughout their line of contact to seal the receptacle thereat (FIGS. 6 and 8). To unfold the cup for return to its flat condition, it is merely necessary to turn the cup members in the opposite directions about their pivot connections 26 until the same arrive at the intermediate stage of FIG. 4, whereupon the cup members are simply slid toward each other until the pivots 36 are at or near the slot ends 38' and the cup members reassume their natural flat condition. Of course, the cup members will on their described turning into folded and unfolded condition be subjected to a snap action from each other which will be fully described hereinafter.

It is the most basic consideration in the design of the present cup that the latter must meet the imperative requirement of being truly leakproof. To this end, the present cup is so designed that the sealing edge 30 of the cup member 22 will respond to the resiliency of both highly flexed cup members in the folded cup by resiliently bearing against and conforming itself to the curved surface of the confronting cup member 24 throughout their unbroken line or area of contact and even at the very apex of the cup receptacle. This is achieved by arranging the cup members and their pivot connections so that lines 1' and 1'' of the cone-shaped cup members 22 and 24 in the folded cup which pass through the apex α of the cup receptacle and thereat extend at right angles to the sealing edge 30 of the cup member 22 (FIG. 6) form within the confines of the cup receptacle an obtuse angle α (FIG. 8). To this end, the cup member 24 is presently shaped so that the slant angle β of its partial cone shape (FIG. 8) is sufficiently large for a substantial depth and, hence, volume of the cup receptacle for the size of the cup members, while the cup member 22 is shaped so that the slant angle γ of its partial cone shape is sufficiently smaller to be consistent with the requirement that the contained angle α of both folded cup members be obtuse. The slant angle β of the folded cup member 24 is in the present example in the neighborhood of 45 degrees, while the slant angle γ of the other folded cup member 22 is quite considerably less than 45 degrees and is in the present example roughly 30 degrees (FIG. 8). To obtain for the cup member 22 the considerably smaller slant angle γ , the aforementioned plane of intersection of the partial cone shape of the cup member, at the line x'' in FIG. 8, in accordance with which the exemplary sealing edge 30 has been laid out so as to conform to the line of intersection x'' in the folded cup, has been spaced correspondingly widely from a plane x''' parallel thereto and passing through the pivot connections 26, as will be readily understood.

In thus shaping the cup members 22 and 24, the same may be folded somewhat beyond the further intermediate stage shown in FIG. 4A before further folding of the cup member 22 is resisted by the other cup member 24 owing to the fact that the sealing edge 30 then enters a constricted region of the partial cone shape of the cup member 24 in which the latter is shorter than the sealing edge

30 across the pivot connections 26. Thus, the cup member 22 will on its further fold encounter at first increasing and then decreasing resistance or interference from the other cup member 24 on its passage through this constricted region of the latter which extends approximately from the point p in FIG. 4A to the point p' in FIG. 8. Accordingly, it is only by additional resilient distortion of the cup member 22 that the same may pass through this interference region of the other cup member 24 without suffering permanent distortion which would render the cup of no further use. This additional, temporary resilient distortion of the cup member 22 is characteristically shown in FIG. 5A by the irregular outline of the sealing edge 30 which indicates that the latter proceeds through the interference region of the cup member 24 in snake fashion best suited for its passage of the latter with the least resistance therefrom. The sealing edge 30 of the folding cup member 22 is thus temporarily distorted in snake or S fashion which characteristically brings about a snap action of this cup member into its normal folded condition (FIGS. 6 and 8) while part of this edge 30 is still within the interference region of the cup member 24. In this connection, the cup member 22 may well be in the condition shown in FIG. 5A just prior to its snap into its normal folded condition (FIGS. 6 and 8), and it is entirely possible that the cup member 22 in FIG. 5A is then in part already in normal folded condition as indicated by the normal folded position of the ear extension 40' and the nearby straight delineation 30'' of part of the sealing edge 30, while the remainder of the cup member is still far from normal folded condition as indicated by the wavy outline of the remainder of the sealing edge 30 and by the illustration of the other ear extension 40'' which has then not folded very much beyond its intermediate folding stage in FIGS. 3 and 4.

The snake-like temporary distortion of the sealing edge 30 is thus quite pronounced and prevails over a substantial part of the passage of the cup member 22 through the constricted region of the other cup member 24. However, it may readily be deduced from FIGS. 5A and 8 that due to the relatively large obtuse angle α between the cup members all along the sealing edge 30 and during the temporary distortion of the latter, the resiliency of a wide marginal portion of the cup member 22 along the edge 30 readily permits the latter to dodge in snake-like fashion through the restricted region of the cup member 24 without encountering much resistance from the latter, yet be resiliently urged against the cup member 24 so uniformly as to conform itself fully to the confronting curvature of the latter already at the stage of FIG. 5A. Thus, the edge 30 in the partly folded cup of FIG. 5A may already seal the same as effectively as it seals the normal folded cup of FIGS. 6 and 8.

It is, of course, the great resilient urgency of the edge 30 of the cup member 22 into contact with the cup member 24 and its self-conformity to the curvature of the latter throughout the folded cup, and even before the same is fully folded, which makes for a most effective seal of the cup receptacle. On the other hand, the great resiliency of the cup member 24 at its edge 30 and its ready conformity to the confronting curvature of the other cup member 24 on folding the cup make for performance of the latter task with the least resistance from the cup member 24 and, hence, with the least effort, and makes it extremely unlikely that either cup member will be permanently distorted on even the clumsiest manipulation. How thoroughly satisfactory the seal of the cup receptacle by the edge 30 really is is further evidenced by the fact that on permitting the preferably considerably over-folded cup members, such as in FIG. 5, for instance, freely to snap back into their normal folded condition (FIG. 6) the sealing edge 30 may readily be observed to have the slightest beginning of a snake-like extent, especially near the receptacle apex α . This clearly indicates that the edge 30 will even resort to snake-like distortion as required to

close any gap therealong as much so at the receptacle apex *a* as at any other place.

As already mentioned, the task of folding and unfolding the cup is greatly facilitated by the inappreciable resistance encountered by the cup member 22 on its passage through the constricted or interference region of the other cup member 24. This task does not even require appreciable manual flexing of the cup members, for the latter will respond by flexing into and from their partial cone shapes largely to harmless and effortless twists of one of their adjacent ends about the pivot connection 26 thereof. Thus, in the course of folding the cup as shown in FIG. 5A, the approximately folded ends at the top may conveniently have been thus folded by holding the cup members some distance inwardly from the top pivot connection 26' and primarily sliding the cup member 22 on the other cup member 24 counterclockwise about the pivot connection 26' until the cup snaps into its normal folded condition very shortly after passing through the condition shown in FIG. 5A.

The arrangement of the floating pivot connections is also advantageous in even further facilitating the task of folding the cup by dividing this task in two distinct successive manipulative steps of exceeding simplicity. Thus, the inclination of the slots 38 to the median line *x* (FIG. 1) is such that they releasably lock the cup members in their preliminary partial cone shapes (FIGS. 3 and 4), with the user of the cup then free to pause and regrasp the cup members for their most convenient further folding into receptacle form as described.

The specific arrangement of the floating pivot connections 26 is further most significant in obtaining a leak-proof seal between the cup members 22 and 24 in their folded cup form. This, it will be noted in FIG. 1 that each pivot 36 on the cup member 22 is spaced considerably inwardly from the edge 28 thereof which is preferably of circular, or nearly circular, outline so as to lie substantially in a plane in the partial cup-shape of the member 22 (FIGS. 7 and 8). Each of these pivots 36 is in any of the folded stages of the members 22 and 24 in FIGS. 3 to 8 similarly widely spaced inwardly from the edge 32 of the other cup member 24 which is also of preferably circular, or nearly circular, outline so as to lie substantially in a plane in the partial cup-shape of the member 24 (FIGS. 7 and 8). In thus having the pivots considerably spaced inwardly from the edges 28 and 32 of the cup members 22 and 24 in any of their folded stages, these cup members will, on their folding beyond the normal cup formation in FIG. 8 to the overfolded condition in FIG. 5, for example, become resiliently flexed increasingly between their pivot connections 26, with their resilient flexure acting on release of either overfolded members 22 and 24 to snap both members back into their cup formation so forcefully that the sealing edge 30 of the member 22 enters the interference region of the other member 24 slightly, but nevertheless sufficiently to become distorted as required in order to close any gap therealong. This explains the earlier described behaviour of the edge 30 of the cup member 22 that it will even resort to snake-like distortion as required to close any gap therealong as much so at the receptacle apex *a* as at any other place. It is, of course, due to the considerable inward spacing of the pivots 36 from the edges 28 and 32 of the cup members 22 and 24 that the latter will, on their over folding beyond cup formation, be compelled into increasingly steeper partial cone formations and, hence, increasing flexure between their pivots 36, and their increasing flexure from this cause is clearly discernible from a comparison between the cup members in their normal cup formation of FIG. 6 and in their exemplary overfolded condition of FIG. 5.

To attain the described effective snap-back of the overfolded cup members 22 and 24 into their cup form, the inward spacing of the pivots 36 from the edges 28 and

32 of these members in any of their folded stages must be quite substantial, and may be as in the exemplary cup shown in the drawings in which they are spaced from the respective edges 28 and 32 a distance of somewhat more than one-fourth of the radius of the substantially circular edge 28 of the cup member 28. In general, effective snap-back of the cup members 22 and 24 from overfolded condition into cup form will be achieved as long as the radius of the substantially circular base-forming edge of either cup member 22 or 24 is no more than several times the distance of either pivot 36 from either nearest edge 28 or 32 of the cup members 22 and 24 in any of their folded stages.

It is in view of this significant substantially equal inward spacing of the pivots from the base-forming edges 28 and 32 of the cup members 22 and 24 in any of their folded stages (FIGS. 3 to 8) and the requirement that the pivot connections 26 permit these cup members to lie flat and superposed when unfolded (FIGS. 1 and 2), that the slots 38 are arranged so that on engagement of the pivots 36 with the slot ends 38'' the former are substantially equally spaced from the base-forming edges of both cup members as desired for their cup formation, while on engagement of the pivots 36 with the opposite slot ends 38' the former are much closer spaced from the base-forming edge 32 of the cup member 24 in order that both cup members may lie flat on each other when unfolded (FIG. 1). It is for these purposes that the slots 38 in the cup member 24 are designed in the first place to slant from their ends 38' to their opposite ends 38'' away from the adjacent base-forming edge 32 of cup member 24 as shown in FIGS. 1, 3 and 7. Of course, the slant of the slots 38 in this respect has further been selected to achieve the previously described camming of the cup members 22 and 24 into and releasable retention in their intermediate folded stage (FIGS. 3 and 4) on merely sliding them apart when unfolded (FIG. 1). Further, while the ear extensions 40 on the cup member 22 will on overfolding of both cup members beyond their cup formation assist somewhat in their snap-back on release into their cup formation, these ear extensions are provided primarily for the purpose of sealing the considerably inwardly spaced slots 38 (FIGS. 6 and 7) and thereby greatly enhancing the leakproof volume of the folded cup.

Finally, reference is had to FIG. 9 which shows a flat folding cup 20a that may in all respects be like the described cup 20, except that the cup member 22a of the present cup lacks the ear extensions 40 of cup 20. The present cup 20a, if in all other respects like the cup 20, would, however leak at the slots 38a but would be leak-proof therebelow in its folded condition.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

A folding cup, comprising two resiliently flexible elongated leaf-like members lying flat on each other when unfolded and having opposite side edges of which opposite first side edges of said members are substantially part-circular, and pivot connections between said members about which to fold them into a cup of complementary partial cones in which said first edges form the bases of the respective partial cones and the other side edge of one of said members bears against the remaining member to seal the cup at the junction of said partial cones, said pivot connections being formed by two pivots on said one member spaced longitudinally thereof and spaced radially inwardly a certain distance from said first edge thereof, and slots in the other member receiving said

pivots, respectively, and having first ends spaced from each other equally as said pivots and spaced less than said distance from said first edge of said other member, and said slots extending toward the other side edge of said other member to their other ends at a slant away from said first edge thereof so as to be spaced substantially said distance therefrom at said other ends, with said other slot ends being spaced apart sufficiently wider than said pivots to cause said slots and pivots to cam said members into and releasably lock them in preliminary partial cone formations on sliding said one member with its pivots to said other slot ends, said certain distance being no more

10

than several times shorter than the radius of said first edge of said one member so that no overfolding of both members beyond their cup form and release of either member both overfolded members will snap back into 5 cup form and seal the same, and opposite ends of said other side edge of said one member are formed by ears on said one member covering said slots in the cup form of said members to seal the cup thereat.
